US00D505177S

(12) **United States Design Patent** (10) Patent No.: **US D505,177 S**
 Fell et al. (45) Date of Patent: **** May 17, 2005**

(54) **QUICK RELEASE MOUNT FOR WEAPONS
WITH RAIL TYPE MOUNTING SYSTEMS
AND OTHER APPLICATIONS**

(76) Inventors: **Oscar M. Fell**, 64 Yacht Haven Dr.,
Cocoa beach, FL (US) 32931; **Michael
Jon Squillante**, 1353 Unter Ave. NW.,
Palm Bay, FL (US) 32907

(**) Term: **14 Years**

(21) Appl. No.: **29/196,960**

(22) Filed: **Jan. 9, 2004**

(51) LOC (7) Cl. **22-01**

(52) U.S. Cl. **D22/110**
